TWIN HULL BOAT

Richard B. Hull, ½ Midland Fiberglass Company,
Box 5714, Midland, Tex. 79701

Filed Feb. 28, 1972, Ser. No. 230,208

Term of patent 14 years

Int. Cl. D12—06
U.S. Cl. D71—1 Q

FIG. 1

FIG. 2

FIG. 3

FIG. 4

FIG. 1 is a perspective view of a twin hull boat made in accordance with the present invention;

FIG. 2 is a perspective front view of the boat disclosed in FIG. 1;

FIG. 3 is a perspective bottom view of the boat illustrated in FIGS. 1 and 2;

FIG. 4 shows a rear perspective view of the boat illustrated in FIGS. 1-3 with the seats and supports omitted for clarity of disclosure.

I claim:

The ornamental design for a twin hull boat, substantially as shown and described.
